NECKTIE HOLDER

Mitchell Winthrop, South Miami, Fla., assignor to
Swank, Inc., a corporation of Delaware

Filed Feb. 5, 1959, Ser. No. 791,330

5 Claims. (Cl. 24—49)

This invention relates to a necktie holder.

One of the objects of this invention is the provision of a necktie holder which will have a mystery effect when positioned on the tie in that two portions of the holder will be separated without any visible means of connection between them from the obverse face of the tie.

Another object of this invention is to provide an ornamental device as well as having the function of holding the necktie in position although allowing some limited movement thereof.

Another object of the invention is to mount the ornament on the tie in an efficient and secure manner.

With these and other objects in view, the invention consists of certain novel features of construction as will be more fully described and particularly pointed out in the appended claims.

In the accompanying drawings:

Figure 1 is a perspective view of a fragmental portion of a necktie with an ornament mounted thereon;

Figure 2 is a perspective view of the holder detached from the tie;

Figure 3 is a perspective exploded view of a necktie holder of a modified form of the invention;

Figure 4 is a perspective exploded view of a still different modification of the invention;

Figure 5 is a perspective exploded view of the invention in still a different form.

In carrying out this invention, I provide a first ornamental member to overlie the obverse face of the necktie and which is provided with a pin to extend rearwardly through the necktie. A spur may also be present to prevent relative rotation of the ornamental member about the pin as an axis. Some clutch means is then provided which will grip the pin and prevent its retraction through the tie. I then provide an arm which is mounted either on the clutch or the part of the pin which extends rearwardly from the back of the tie, which will extend along the rear surface of the necktie and then forwardly about the edge of the necktie, and on this forwardly extending portion of the arm, I provide a second ornamental member which will usually be of a form to cooperate in ornamental theme with the first ornamental member. This second ornamental member overlies the obverse face of the necktie adjacent the edge thereof and serves by embracing the edge of the tie to retain the tie. The clutch will be tethered to the shirt of the wearer to prevent excessive lateral movement of the tie. In some cases two arms may be provided extending in opposite directions, and in that case opposite edges of the tie may be embraced rather than a single edge.

With reference to the drawings, 10 designates a first ornamental member which in the case of Figures 1 and 2 is shown as a bowling pin. Extending rearwardly from this bowling pin, there is a pin 11 which will pierce or extend through the necktie and project beyond the rear surface thereof. A clutch 12 of a type well known in the trade having balls which will be urged along a

tapered surface to grip the pin is provided and which clutch has a releasing cage operated by a handle 13. This clutch is utilized for gripping the pin and preventing its withdrawal from the tie and acts as an anchor 5 member for the pin.

An arm 14 is secured to the clutch body 12 and extends in a plane perpendicular to the pin 11. At a point spaced from the pin, the arm has a forwardly extending portion 15 which will project along and engage the edge 10 16 of the necktie as shown in Figure 1. On the forward end of this forwardly projecting portion, a second ornament 17 is mounted, in this case by means of a finger 18 which attaches to the ornament 17 which is the figure of a man in the act of throwing a bowling ball 15 19 as there shown. This second ornamental member 17 also extends over the obverse face of the necktie adjacent the edge thereof and serves to retain this edge of the necktie in position. In order to tether the necktie against excessive movement, a chain 20 is secured to an eye 21 attached to the clutch and is provided with a crossbar 22 to secure the end of the chain to the button hole of the shirt beneath the necktie.

In Figure 3 I have illustrated the first ornamental member now designated 23 as the upper portion of a sword having a handle 24, a cross piece 25 and the portion of a shank 26. From this ornamental member the pin 11 as above described extends to pass rearwardly through the necktie while a spur 27 is shown to also enter the necktie and prevent the member from rotating 30 about the pin 11 as an axis. The clutch 12 having its handle 13 is illustrated the same as in Figure 2, and an arm 14 is shown as extending from the clutch with its forwardly extending portion 15. In this case, however, the second ornamental member, designated 28, is in the 35 shape of the lower or pointed end of the sword and is mounted on the portion 15 so as to extend in line with the first ornamental member and over the obverse face of the necktie adjacent the edge 16 thereof. In this case the point 29 of the member will project outwardly beyond the edge of the tie.

In Figure 4 I have illustrated the first ornamental member 30 as the letter of an alphabet. Projecting rearwardly therefrom is the pin 11 while there is also provided a spur 27 extending rearwardly thereof to prevent rotation of the ornamental member. The second ornamental member 31 in this case is also a letter of the alphabet. In this case however the arm 32 which has a forwardly extending portion 33 attached to the ornamental member 31 is provided with a plurality of 45 openings 34, any selected one of which the pin 11 may pass through. This necessitates the clutch 12 being separated from the arm 32 and attached to the pin 11 after it has passed through the selected opening 34.

In Figure 5 the first ornamental member is shown in 50 the shape of a sphere 35 having a pin 11 extending rearwardly therefrom. Inasmuch as this ornamental member is a sphere, it is unnecessary to provide a spur to prevent its relative rotation, although, if desired, this may be done. The clutch 12 and its operating handle 13 is 55 provided as heretofore, while there is the arm 14 with its forwardly extending portion 15. The second ornamental member here designated as 36 is shown in the shape of a triangle pointing to the sphere 35. In this case, however, the arm 14 is duplicated as shown at 14' with a forwardly extending portion 15' and a duplicate ornament 36' formed diametrically opposite and in balanced relation to the arm 14. In this case as in 60 all cases the clutch will be tethered to the shirt as described in connection with Figure 2.

By this arrangement the ornamental necktie holder 65 may be formed as two cooperating parts which may have the appearance of being completely separated in their

mounting on the tie which lends itself to artistic ornamental themes attractive in jewelry, as well as providing a utilitarian tie holder.

I claim:

1. A necktie holder comprising a first ornamental member to overlie the obverse face of the necktie and having a pin with a sharp point to pass rearwardly through the necktie, an anchor member to releasably grip the pin and prevent its withdrawal through the tie, and an arm in a plane extending generally perpendicular to said pin and held thereto, said arm at a location spaced from the pin having a portion extending forwardly generally parallel to the pin and means comprising a second ornament carried by the said portion of said arm to overlie the face of the necktie adjacent an edge thereof, and means to tether said anchor to the shirt of the wearer. 15

2. A necktie holder as in claim 1 wherein the first member has a spur spaced from the pin to enter the necktie and prevent rotation of the member about the pin as an axis. 20

3. A necktie holder as in claim 1 wherein said arm has a plurality of openings through a selected one of which said pin passes.

5. A necktie holder as in claim 1 wherein said arm is secured to said anchor member.

5. A necktie holder as in claim 1 wherein a second similar arm extends in said plane on the other side of said pin and carries on a forwardly extending portion a third ornament overlying the face of the necktie adjacent the opposite edge of the necktie. 10
